DESIGN FOR A GAME SCORING DEVICE

Walter L. Mann, Phillipston, Mass.

Application March 28, 1935, Serial No. 56,102

Term of patent 7 years

To all whom it may concern:

Be it known that I, Walter L. Mann, a citizen of the United States, residing at Phillipston in the county of Worcester and State of Massachusetts, have invented a new, original, and ornamental Design for a Game Scoring Device, of which the following is a specification, reference being had to the accompanying drawing, forming part thereof.

Fig. 1 is a perspective view of a game scoring device showing my new design;

Fig. 2 is a partial front view, and

Fig. 3 is a fragmentary sectional end elevation.

I claim:

The ornamental design for a game scoring device as shown.

WALTER L. MANN.
